A. VAN CAMP, OF WASHINGTON, DISTRICT OF COLUMBIA, AND M. M. HODGMAN, OF ST. LOUIS, MISSOURI.

Letters Patent No. 97,020, dated November 16, 1869.

IMPROVED STREET-RAILWAY.

The Schedule referred to in these Letters Patent and making part of the same.

To all whom it may concern:

Be it known that we, A. VAN CAMP, of Washington city, and District of Columbia, and M. M. HODGMAN, of St. Louis, in the county of St. Louis, and State of Missouri, have invented a new and useful Improvement in Railways; and we do hereby declare that the following is a full, clear, and exact description of the same, reference being had to the accompanying drawing, and to the letters of reference marked thereon, making part of this specification, in which is shown a sectional view through the rail, clearly illustrating how the same is embedded and securely held in the concrete.

The nature of our invention consists in securing railroad-rails, by embedding the same in a concrete pavement or bed, composed of the composition described in my patent of July 27, 1869.

As the rails are intended to be firmly laid, without the assistance of cross-ties, spikes, or any other like appliances, only such rails can be advantageously used as are provided with suitable bearing-surfaces for the concrete to adhere to.

The rail hereinafter described, and which is constructed with a deep centre bearing-plate, the surface of which is to be corrugated or roughened, is admirably adapted to the purpose. But practical experience has fully attested the fact that the T-shaped, and other like rails now in common use, can readily be so embedded in concrete as to be firmly secured therein, the form of these rails being such that the necessary bearing-surface is provided, and their flanges, by means of which the rails are now connected to the cross-ties, becoming securely fastened in the concrete, a desirable and permanent lodgement is effected.

To properly secure the rail in the concrete, its entire under surface is to be completely embedded, only so much of its surface as is required for the tread of the wheel being left exposed, and it on a line of flush with the pavement or upper surface of the bed.

After the rail has been laid, the necessary groove for the flange of the wheel to run in can readily be provided.

Practical experience has fully attested the fact that the composition embraced in and covered by our patent of July 27, 1869, for "improvement in concrete pavements," is admirably adapted for the purpose designed in our present invention.

The concrete referred to is, when once laid, entirely unyielding in its nature, and most adhesive in its character, and is unaffected by either heat or cold, rain or frost, as has been fully demonstrated by practical tests.

To enable others skilled in the art to make and use our invention, we will now proceed to describe its construction and operation.

A is a railroad-rail, and may be formed by casting, rolling, or by any other suitable means.

This rail A is provided with a centre bearing-plate, A', the surfaces of which are corrugated, as seen at a a.

The rail thus constructed is entirely embedded in the concrete pavement or bed B, only so much of the same being left exposed as is required for the tread of the wheel.

The process of securing the rails is as follows:

The crushed stone or rock and asphaltum are mixed and heated according to the formula, and in the manner stated in our patent of July 27, 1869.

A thin layer, b, of the concrete is then laid and thoroughly rammed by the hot tamps. This serves as a bed for the under surface of the bearing-plate A', to rest on.

After the rails have been properly seated, more of the composition, in a hot, plastic state, is poured down and rammed by the tamps or other suitable implement.

Then add more of the composition, and repeat the ramming-process, or use the heated rollers, as described in our patent before referred to.

This is continued until the composition, in a thoroughly compact condition, is flush with the upper surface of the rail. After the rail has been thus secured, a suitable groove, C, is formed for the flange of the car-wheel to run in. This groove can readily be made simply by passing a thoroughly heated rod, or other suitable implement, along the side of the rail and through the composition.

Instead of the bearing-plate A', having corrugations a a, as shown, its surface may be in any other manner roughened or rendered uneven, the only advantage of the corrugations being to provide a surface that has numerous recesses or interstices for the composition to enter and embed itself.

Having thus fully described our invention,

What we claim therein as new, and desire to secure by Letters Patent of the United States, is—

The rail A, having a centre bearing-surface, A', when the same is laid or embedded in concrete B, substantially as described.

In testimony whereof, we have signed our names to this specification, in the presence of two subscribing witnesses.

A. VAN CAMP.
M. M. HODGMAN.
